UNITED STATES PATENT OFFICE.

PEARL J. WENTWORTH, OF BOSTON, MASSACHUSETTS, ASSIGNOR TO UNITED SHOE MACHINERY COMPANY, OF PATERSON, NEW JERSEY, A CORPORATION OF NEW JERSEY.

UPPER-PULLING MECHANISM.

1,139,613.

Specification of Letters Patent. Patented May 18, 1915.

Application filed April 14, 1911, Serial No. 621,104. Renewed December 11, 1911. Serial No. 665,027.

To all whom it may concern:

Be it known that I, PEARL J. WENTWORTH, a citizen of the United States, residing at Boston, in the county of Suffolk and State 5 of Massachusetts, have invented certain Improvements in Upper-Pulling Mechanisms, of which the following description, in connection with the accompanying drawings, is a specification, like reference characters 10 on the drawings indicating like parts in the several figures.

This invention relates to apparatus for use in the manufacture of boots and shoes, for pulling an upper on a last and is herein 15 shown by way of exemplification as embodied in a tip puller for use in connection with pulling-over machines of the type shown in United States Letters Patent 663,777 although certain broad features of 20 the invention are applicable generally to means for pulling an upper on a last. Referring first to the field of utility for which the illustrated construction has been designed, it is frequently necessary before presenting a shoe to the pulling-over machine, on account of the short length of the uppers, and generally desirable for good shoe making, to draw the upper as a whole forwardly, thereby setting the heel portion of the upper 25 upon the last. It has been the custom of many operators to spindle the last and, with the shoe then supported sole uppermost, to pull the upper at the toe forwardly by hand pincers. This is a comparatively 30 slow and troublesome operation and is often neglected by operators when it should be performed.

The broad object of this invention is to 40 improve upper gripping or gripping and pulling means generally wherever the principle of this invention is applicable and more specifically the object is to provide a tip puller which shall be so convenient to use that the tip pulling operation shall not be a burdensome one to the operator and a 45 puller which shall produce better results than have been obtained by the old practice and which consists in a machine for gripping and pulling an upper on a last comprising relatively movable gripping jaws and means for causing closure of the jaws to be effected which is arranged so that it 50 can be operated by the last, as, for example, pressure of the last bottom, with or without provision whereby further pressure or ful-

crumming of the last over said means may be made to effect pulling of the gripped upper between the jaws and the last.

A more specific feature of the invention is found in a tip puller that can stand upright upon the bench of the machine, to which it is preferably fastened, with its jaws opening upward and forward toward the operator, so that the top or toe of the upper can be readily thrust into the puller 65 and seized with the top of the shoe in plain view, so that the effect of the stretching can be observed.

A further feature of the invention consists in arrangements such as those herein-after described or their functional equivalents for automatically closing the jaws and effecting pulling of the upper simply by pressure of the shoe and as shown this feature is embodied in means comprising a 70 rigid jaw and a movable jaw and means for causing closure of the jaws arranged to be operated by movement of the last. As shown, one of the jaws is connected to an arm upon which the shoe bottom is made to 75 engage for closing that jaw toward a fixed jaw. Also as shown the arm of that jaw has a fulcrum block or projection about which the shoe can be pivoted to raise the toe of the last for effecting the stretching of the upper. 80 These parts are so arranged and constructed, as will more fully appear from the detailed description and the drawings, that the operator can grasp the shoe over the instep, as he is accustomed to do for presenting it 85 to the pulling-over machine, and while presenting it to the tip puller and rocking the last to stretch the upper can hold the upper against the top face of the last over the ball with his forefinger to maintain the upper 90 in lengthwise stretched position while he frees the shoe from the tip puller and presents it to the grippers of the pulling-over machine. He can thus, with a single series 95 of movements requiring the use of only one hand, pick up the shoe, pull the tip and hold the upper forward on the last until it is seized by the jaws of the machine. Also he can observe the preliminary pulling and see that the tip seam is not bowed or pulled 100 so that it will be bowed in the pulling machine. The fixed jaw of the tip puller is formed on an arm to which the other jaw is fulcrumed and which is pivoted to a base 105 for adjustment of the jaws into different 110

angular positions to suit the height or preference of individual operators. This is of importance in view of the attitude which the operator should, for convenience and best results, assume toward the shoe while he is pulling the tip.

The several features of the invention, including certain combinations of parts and more important details of construction of the illustrated embodiment of the invention will now be described in connection with the drawings and then be pointed out in the claims.

Figure 1 is a side elevation of the tip puller with a shoe held in position thereon; Fig. 2 shows the same shoe being presented, without release of the operator's grip thereon, to the pulling-over machine.

The tip puller, as shown, comprises a base 20 adapted to be fastened to the usual workman's bench of a pulling-over machine. From the base rise standards 4 between which the arm 5 is mounted on a pivot pin 6. The lower end of the arm has a bolt hole by 25 which it can be secured in adjusted relation to either one of a series of holes 8 arranged in an arc in one of the standards. Above the standards the arm 5 is extended and shaped to form the normally stationary or fixed 30 jaw 10 which is provided on its upwardly and rearwardly inclined face with backwardly directed teeth or serrations. The arm 5 is recessed from front to rear to receive the jaw 12 which is pivoted at 13 and 35 extended upwardly and rearwardly over the jaw 10. Jaw 12 is also preferably extended farther to provide the finger 15 above the gripping faces of the jaws to facilitate the entrance of the upper into the 40 jaws when the shoe is thrust toward them for the purpose of having the tip seized. Jaw 12 also has an arm 16 extending from the pivot pin rearwardly under the shoe to receive pressure from the shoe to close the 45 jaw 12 upon the upper. A fulcrum block 20 is mounted on the arm 16 and can be secured in adjusted position with reference to the jaws by a binding screw 22. As shown, the fulcrum block can slide on the arm 16 50 for adjustment. A spring 24 holds the jaws normally open.

In use the operator picks up the assembled shoe from the rack, grasping it about the instep or waist, and can with one hand thrust 55 it forwardly until it engages the finger 15 and then downwardly until the tip of the upper is guided into the jaws and the shoe bottom engages the fulcrum block, and by rocking the arm 16 downwardly causes the 60 upper to be seized without any special attention from the operator. Further downward pressure after the upper is seized causes the shoe to rock about the fulcrum block 20 and the upper to be pulled in proportion to the 65 pressure applied. The force applied may

be considerable and it is contemplated that the machine shall be secured to a bench or other rigid support, the last being used as a lever to tension the upper. The operator watches the progress of the stretching and, 70 while continuing it to the desired extent, avoids bowing the tip seam. He can also, by turning the last to the left or the right, straighten the tip if it is aslant on the last. In this way the shoe can be so prepared for 75 presentation to the pulling-over machine that the adjustments and other manual manipulation to secure proper pulling over are reduced to a minimum. The operator rocks the shoe to pull the upper with his forefinger on the top of the shoe adjacent to the tip seam, and by this finger clamps the pulled upper to the last and then, lifting the shoe to cause the pincers to free the tip, carries the shoe upwardly to the gripper 80 jaws and sole rest of the pulling-over machine. It will be noted that only a single handling of the shoe, in fact a single seizing of the shoe and a continuous series of movements of it which can be conveniently effected, is required in transferring the shoe from its rack to the jaws of the pulling machine, and that during this procedure the tip is pulled more effectively and better than by the relatively slow and awkward method of 85 spindling the shoe sole uppermost and pulling the tip by hand pincers. The arms 5 can be adjusted into that one of the holes 8 which will bring the jaws at the right height 90 for the individual operator to position the shoe in the jaws and rock it most conveniently and the fulcrum block 20 may be adjusted to give the desired leverage. 95

Preferably and as herein shown the jaw 10 which engages the lining has teeth faced inwardly, and the other jaw 12 has interlocking teeth that face outwardly. This reduces liability of scarring the upper while injury to the lining is not to be feared. The guide 15 has its working face in the plane of the teeth on jaw 12 or in a plane even a little closer to jaw 10. By making the guide with its working face as high as the teeth on jaw 12 liability is reduced of the edge of the tip 100 catching on the outwardly faced teeth as might otherwise occur in quickly inserting the work. 110

Having described my invention, what I claim as new and desire to secure by Letters Patent of the United States is:—

1. Means for pulling an upper on a last, having in combination, a fixed jaw, a pivoted jaw having a finger extending above the fixed jaw and against which the end of the shoe may be abutted to guide the upper between the jaws, and means through which movements may be had to close the jaws and to pull the upper. 125

2. Apparatus for pulling an upper, having, in combination, a base arranged to be 130

- secured to a support, a gripper jaw fixed thereon, a coöperating gripper jaw pivotally supported by said base and movable against the fixed jaw to seize an upper, and means 5 connected with the pivoted jaw and arranged to be engaged by the shoe to effect upper seizing movement of the pivoted jaw by force transmitted from the shoe through said means.
- 10 3. Apparatus for pulling an upper on a last, having, in combination, a base arranged to be secured to a support, a gripper jaw thereon, and a coöperating gripper jaw pivoted relatively to the base jaw and having a 15 rearwardly extending arm provided with a shoe bottom resting face to receive pressure from the last to swing the arm to close the jaws.
4. Apparatus for pulling an upper on a 20 last, having, in combination, a base arranged to be secured to a support, a lower gripping jaw stationary relative to the base, and an upper jaw movable toward the fixed jaw and having an operating arm extending at a 25 substantial angle to the gripping face of the upper jaw and upon which a shoe can be rested to effect closing of the jaws and which is formed to permit the last that is within the shoe to be fulcrumed thereon to pull the 30 upper between the jaws and the last.
5. Apparatus for pulling an upper on a last, having, in combination, a base arranged to be secured to a support, a stationary jaw thereon, a companion jaw pivoted to the 35 base and having an angular arm, and a shoe rest on the arm substantially as and for the purpose described.
6. Apparatus for pulling an upper on a 40 last, having, in combination, a base, a stationary jaw on the base, a companion jaw pivoted adjacent to the stationary jaw and having an angular arm, and a shoe rest on the arm, said rest being adjustable from and 45 toward the jaws.
7. Means for pulling an upper on a last, having in combination, a base, an arm having a jaw at its upper end and angularly adjustable in the base to change the plane of the jaw, a second jaw pivoted to the first one, and means to actuate the second jaw. 50
8. Means for pulling an upper on a last having gripping jaws, a toe end abutment to be engaged by an endwise movement of the shoe, and a jaw operator to be actuated by downward pressure of the shoe. 55
9. Means for pulling an upper on a last having gripping jaws, a toe end abutment to be engaged by an endwise movement of the shoe, and a jaw operating lever to be actuated by downward pressure of the shoe, said lever having a fulcrum rest about which the shoe can be rocked to pull the upper between the jaws and the last. 60
10. Means for pulling an upper on a last, 65
- having in combination, a base having standards, an arm pivoted between the standards with its lower end adjustably secured in the base and having a gripping jaw on its upper end inclined more or less to the vertical 70 according to the adjustment of the lower end of the arm, a gripping jaw pivoted to the upper portion of the arm and having an arm extending substantially at right angles to the gripping face of the pivoted jaw, and 75 a fulcrum rest adjustable on the arm toward and from the jaws.
11. A tip puller for a pulling-over machine having a base, a fulcrum rest in position to receive a shoe with its sole down 80 and its top face before the operator, a gripping jaw connected with said rest for operation by pressure of the shoe, and a rigid jaw on said base and between which and the movable jaw the tip of the upper is gripped 85 by the pressure of the shoe and pulled by rocking of the shoe on the rest, said parts being arranged to enable the operator to clamp the pulled upper to the last adjacent to the tip seam by the forefinger of the hand 90 that grasps the shoe, to release the shoe, and to lift it with the upper so clamped into the pulling-over machine.
12. Means for pulling an upper on a last, 95 having in combination, two jaws arranged for operation to seize the work, one of said jaws having a toothed gripping face and a guide located relatively to said toothed face to facilitate the insertion of the tip and having its working face adjacent to the toothed 100 surface of the jaw as high as the teeth to prevent the work from catching as it is inserted.
13. Means for pulling an upper on a last comprising a base arranged to be secured to a support, a jaw rigid therewith, a movable jaw, and means for causing closure of the 105 jaws arranged to be operated by the shoe.
14. Apparatus of the class described having, in combination, a gripping jaw, means arranged to be secured to a support and by which said jaw may be fixed in position, a rest for a shoe bottom movable relatively to said jaw by the shoe, and a second jaw operatively connected with said rest to be moved thereby to grip the upper of a shoe pressed against the rest. 110
15. Apparatus of the class described having, in combination, a gripping jaw, means 120 arranged to be secured to a support and by which said jaw may be fixed in position, means arranged to serve as a rest for engagement by the bottom of a shoe on a last and formed to permit the shoe to be tipped 125 upon it as a fulcrum, said resting means being movable relatively to said jaw in response to pressure of the shoe that is rested thereon, and a coöperating jaw operatively connected to said resting means for move- 130

- 4
- ment thereby to grip the edge of an upper located on the last and to be held in gripping engagement with the upper by the pressure of the last on the resting means as 10 the last is tipped away from the jaws to stretch the upper.
16. A pincer formed for attachment to a work bench and comprising a forwardly and upwardly extending jaw with a gripping face on its rear side and adapted to extend between a last and an upper on the last, a rest which is located for engagement by the bottom of the shoe so presented to said jaw, is mounted to permit downward 15 movement by the shoe pressed against it and is arranged to allow the shoe to be rocked upon it, and an outer jaw operatively connected with said rest for movement thereby to engage the outer side of the upper and 20 grip it against the inner jaw and hold the edge of the upper while the last is rocked to stretch the upper between the jaws and the last.
17. Means for pulling an upper on a last 25 comprising relatively movable gripping jaws adapted to receive the margin of an upper when the shoe is presented thereto in the hand of a workman, means comprising an angle lever one arm of which is 30 formed as one of the jaws and the other arm as a sole rest against which the shoe may be pressed to effect closing movement of the jaws and about which the shoe may be turned to tension the upper on the last, and 35 a jaw carrying base arranged to be secured to a support and by which the jaws are mounted in position for the described presentation and manipulation of the shoe.
18. Means for pulling an upper compris- 100
- ing a sustaining member arranged to be secured to a support, relatively movable jaws connected with said sustaining member, and means arranged to be engaged by the toe end and by the sole face of the shoe as presented and against which the shoe is 45 guided and pressed for closing the jaws and then pulling the upper.
19. Means for pulling an upper comprising relatively movable jaws and means arranged to be engaged by the shoe as the upper thereof is presented to the jaws for closing the jaws and for acting as a fulcrum about which the shoe may be moved for tensioning the upper, and means located beyond the gripping face of the outer jaw 50 and against which the last may be steadied in proper longitudinal position while the jaws are being closed upon the upper.
20. Apparatus of the class described, having, in combination, a rest to be engaged by the sole face of a shoe, and jaws having roughened gripping faces extending at an oblique angle to the sole engaging face of the rest for engagement with the edge of an upper loosely applied to a last, the jaw engaging the outer finished side of the upper leather having a non-abrasive upward extension beyond its gripping face arranged to guide the work into position to be operated upon.

In testimony whereof I have signed my name to this specification in the presence of two subscribing witnesses.
